(57) **CLAIM**

The ornamental design for a finger grip for syringe, as shown and described.

DESCRIPTION

FIG. 1 is a front elevation view of a finger grip for syringe according to our new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a cross sectional view taken across line 7-7 of FIG. 1;

FIG. 8 is a cross-sectional view taken across line 8-8 of FIG. 5;

FIG. 9 is a cross-sectional view taken across line 9-9 of FIG. 1;

FIG. 10 is a front perspective view showing an example use thereof; and,

FIG. 11 is a rear perspective view showing an example use thereof.

The broken lines shown in the drawings illustrate environmental structure that forms no part of the claimed design.

1 Claim, 4 Drawing Sheets
